UNITED STATES PATENT OFFICE.

ARTHUR M. LEISSE, OF ST. LOUIS, MISSOURI.

FENDER.

Application filed August 29, 1924. Serial No. 734,866.

To all whom it may concern:

Be it known that I, ARTHUR M. LEISSE, a citizen of the United States, residing at the city of St. Louis, in the State of Missouri, have invented certain new and useful Improvements in Fenders, of which the following is a specification.

This invention relates to fenders for vehicles, such as street cars, automobiles and the like.

One of the objects of the present invention is to provide a fender which will lower automatically when impacted by an obstacle.

Another object is the provision of means whereby the fender will automatically lift the object struck thereby and carry the same.

Another purpose is to provide means for adjusting the fender to operate in any desired position.

Another object is to provide a fender which will when colliding with an animal or person, yield sufficiently under the force of the impact to prevent serious injury thereto.

It is further aimed to supplement the automatic features of the fender by means whereby it may be operated manually, thus insuring positive action should the automatic operation fail for any reason.

Another object is to provide a fender which, while possessing the foregoing characteristics, will at the same time be simple in construction and operation, as well as being durable and reliable.

Other objects and advantages will appear as the description proceeds.

In the accompanying drawings forming part of this specification, in which like numbers of reference denote like parts wherever they occur,

Figure 1 is a front view of the fender as it appears when applied to an automobile;

Figure 2 is a vertical sectional view taken on the line 2—2 in Figure 1.

A pair of supporting frames or brackets 1 are secured at their lower ends preferably to the front axle 2 of a motor vehicle, by means of bolts 3, which pass through the caps 4 and are threaded into feet or lugs 5 of the brackets 1, thus clamping the axle 2 between the caps 4 and the feet 5. The brackets 1 are preferably mounted at each side of the hood 6. The upper end of the brackets 1 contain mutually alined bearings 7, in which are journaled pivot pins 8, formed integral or in fixed relation to a frame 9 depending therefrom.

The frame 9 comprises short arms 10, projecting forwardly from the pins 8, a horizontal upper bar 11 extending transversely across the front of the vehicle and fixed to the front ends of the arms 10, depending arms 12, fixed at their upper ends to the pins 8 and having their lower ends 13 bent over at right angles toward one another, and bars 14 connecting the opposing arms 12 intermediate.

Washers 15 of soft material gripped on either side by serrated washers 16 of hard material are interposed between the arms 10 and bearings 7 on the pins 8, and nuts 17 on the inwardly projecting threaded ends 18 of the pins 8 bear against the inner sides of the bosses 7 to clamp frame 9 in fixed relation to the brackets 1. This method of clamping at the pivotal point, however, is insufficient to prevent the rearward swinging of the frame 9 should the fender suddenly meet an obstacle, and, therefore, additional means are provided to limit the rearward movement of the frame 9. Such means comprises

the arms 19, projecting from the brackets 1 towards a bar 14, preferably the lower one, of the frame 9. The arm 19 is bifurcated at its forward end, the rod 14 entering between the prongs 20 into a wedge-shaped slot 21, formed by the spreading of the prongs 20. When the fender is impacted, the shock is mitigated by reason of the rod 14 yielding under pressure to wedge further into the slot 21, spreading the resilient prongs 20 further apart, and thus more gradually absorbing the kinetic energy of the impact because of the resulting progressively increasing friction of the rod 14 on the prongs 20.

Arms 22 are pivoted about the ends 13, which ends 13 are threaded for the reception of tightly fitting nuts 23 adjacent the outer sides of the arms 22, and loosely fitting adjusting nuts 24 and check nuts 25 adjacent the inner sides of the arms 22. Arms 22 are braced together by rod 26 near the ends 13, and by a fender lower bar 27 at their free ends.

Flexible strips 28 are arranged transversely to the bars 11 and 27, being fixed in any common manner as by welding, at their upper ends to upper bar 11, and at their lower ends to lower bar 27. Strips or bands 29, preferably formed of spring steel and normally bent arcuate as shown in full lines in Figure 2, assist in maintaining the fender in normal initial position. The flexible

strips 28 may, also, be of steel, and may, also, be resilient in the direction of flexure, and bent arcuate, as are the strips 28. Preferably, however, the burden of maintaining the fender in normal position should devolve on the strips 29.

The operation is as follows: The fender is normally in the position indicated by full lines in Figure 2, the bar 27 being at a suitable height so as to clear irregularities in the surface of the road. Free vibration of the arms 22 and bar 27 is prevented by suitably adjusting nuts 24 and 25 to create sufficient friction between the arms 22 and the nuts on either side thereof. Arms 22 may, also, be adjusted to positions above or below normal, and held thereto by suitable pressure of nuts 23, 24, and 25. When a body is struck by bar 27, the impact lowers bar 27 and stretches flexible members 28, thereby decreasing the opening between bar 27 and the surface of the road and minimizing the possibility of the fender passing over the body, as shown in dotted lines in Figure 2. The lower part of the body is thus carried forward in advance of its upper part, which upper part is subsequently impacted by an intermediate part of the strips 28, causing the strips 28 to yield under the impact and assume the lifted extreme arcuate position shown in broken lines in Figure 2, thus lifting the body and carrying it, instead of dragging it along the road. The fender may be operated manually by a lever 30, within convenient reach of the operator, fulcrumed at 31 to a bracket 32, secured, preferably, to the underside of the vehicle floor 33. The lower arm of the lever 30 is pivoted at 34 to a link 35, pivoted at 36 to arm 37, integral with arm 22.

The pin 36 may be removed from the arm 37, thereby disconnecting link 35 and arm 37, whereby, upon loosening nuts 17, the frame 9 and associated parts may be swung upwardly about the pivot 8 and over the hood 6 of the car, thereby permitting access to the inner side of the fender and the front of the car normally covered thereby for purposes of repairs and the like.

Having thus described this invention, I hereby reserve the benefit of all changes in form, arrangement, order, or use of parts, as it is evident that many minor changes may be made therein without departing from the spirit of this invention or the scope of the following claims.

I claim:

1. A fender comprising a pair of elements diverging from a mutual pivotal connection, and flexible fending means connecting the diverging portions of said elements, and limiting swinging movement of said elements away from each other and then causing one element to swing back towards the other element to a point beyond its normal position

for flexing of the flexible means into a pocket formation.

2. In a fender, upper and lower elements diverging from a mutual pivotal connection, spring means normally tending to maintain said elements in a predetermined initial position and yieldably prevent movement in a diverging direction, and flexible fending and catching means carried by said upper and lower elements.

3. The combination of a supporting member, a fender having an upper portion pivoted to the supporting member and a lower portion pivoted to the upper portion, means for restraining the lower fender portion from movement in one direction, and fending and catching means carried by the fender portions and adapted to be drawn tight when striking an object and upon catching the object to be moved to cause return of the lower fender portion to a point beyond its normal position.

4. The combination of a supporting member, a fender having an upper portion pivoted to the supporting member and a lower portion pivoted to the upper portion, means for limiting the rearward swing of the said upper portion of said fender, means for yieldably preventing swinging of the upper and lower portions in one direction from their point of pivoted connection to each other, and flexible fending means carried by the said fender portions.

5. The combination of a supporting member and a fending member pivoted thereto, each of said members bearing a frictional surface which wedges against the frictional surface of the other to limit the movement in one direction.

6. In a fender construction, mounting means adapted for connection with the front end of a vehicle, an upper frame member pivotally mounted at its upper end by said mounting means, a lower frame member pivotally connected with the lower portion of the upper frame member, said mounting means being provided with means for engaging the upper frame member and limiting rearward movement thereof, resilient strips secured to the upper portion of the upper frame member and to the lower portion of the lower frame member and yieldably resisting rearward swinging movement of the lower frame member, and flexible body-engaging and supporting means carried by the upper and lower frame members and limiting rearward swinging of the lower frame member relative to the upper frame member.

7. In a fender construction, mounting brackets adapted for connection with the forward portion of a vehicle at opposite sides thereof in a vertical position and having forwardly extending arms provided with yieldable fingers, a frame having an

upper member pivoted at its upper end to the upper ends of said brackets and a lower member pivoted to the lower end of the upper frame member, said upper frame member having abutment means for engaging said fingers and limiting rearward swinging of the upper frame member, resilient means yieldably resisting rearward swinging of the lower frame member, and flexible body-engaging and carrying means carried by said frame and controlling swinging movement of the lower frame members.

8. A fender comprising an upper bar and a lower bar, a plurality of flexible elements connecting the said bars, an arm projecting from the lower bar, and another arm projecting from the upper bar, the said arms being pivoted one to the other.

9. A fender comprising an upper bar and a lower bar, a plurality of resiliently flexible elements connecting the said bars, an arm projecting from the lower bar and another arm projecting from the upper bar, the said arms being pivotally connected one to the other.

10. In a fender, the combination with a support, of a frame pivotally depending therefrom and comprising an upper bar and a pair of depending arms, a frame comprising a lower bar and a pair of arms in pivotal relation to the said depending arms of the first-mentioned frame, and a plurality of flexible strips connecting the said bars.

11. In a fender, the combination with a support, of a frame pivotally depending therefrom and comprising an upper bar and a pair of depending arms, a frame comprising a lower bar and a pair of arms in pivotal relation to the said depending arms, and a plurality of normally arcuate resiliently flexible strips connecting the said bars.

12. In a fender, the combination with a supporting frame, of a second frame pivotally depending therefrom and comprising an upper bar and a pair of depending arms, each of said frames having a frictional surface which wedges against the frictional surface of the other to limit the rearward swing of the second frame, a third frame comprising a lower bar and a pair of arms in pivotal relation to the said depending arms of the second frame, and a plurality of flexible strips connecting the said bars.

13. In a fender, the combination with a supporting frame presenting a wedge-shaped slot; a second frame pivotally depending therefrom and comprising an upper bar, a pair of depending arms, and a second bar connecting the said arms and adapted for engaging the said wedge-shaped slot to limit the movement of said second frame; a third frame comprising a lower bar and a pair of arms pivoted to the said

depending arms; and a plurality of flexible strips connecting the said upper and lower bars.

14. In a fender, a pair of frames, each of which presents an arm which is pivoted to an arm of the other, screw means for adjusting the friction at the pivots of said arms, and flexible strips connecting said frames.

15. In a fender, a pair of frames, each of which presents an arm which is pivoted to an arm of the other, screw means for adjusting the friction at the pivots of said arms, and resiliently flexible strips connecting said frames.

16. In a fender, a pair of frames, each of which presents an arm which is pivoted to an arm of the other, screw means for adjusting the friction at the pivots of said arms, and normally arcuate resiliently flexible strips connecting said frames.

17. In a fender, the combination with a support, of a frame pivoted thereto and comprising an upper bar and a pair of depending arms, a second frame comprising a lower bar and a pair of arms pivoted to the said depending arms, screw means for adjusting the friction at the pivots of said arms, and flexible strips connecting said bars.

18. In a fender, the combination with a support, of a frame pivoted thereto and comprising an upper bar and a pair of depending arms, a second frame comprising a lower bar and a pair of arms pivoted to the said depending arms, screw means for adjusting the friction at the pivots of said arms, and resiliently flexible strips connecting said bars.

19. In a fender, the combination with a support, of a frame pivoted thereto and comprising an upper bar and a pair of depending arms, a second frame comprising a lower bar and a pair of arms pivoted to the said depending arms, screw means for adjusting the friction at the pivots of said arms, and normally arcuate resiliently flexible strips connecting said bars.

20. In a fender, the combination with a supporting frame, of a second frame pivoted thereto and comprising an upper bar and a pair of depending arms, each of said frames having a frictional surface which wedges against the frictional surface of the other to limit the rearward movement of the second frame, a third frame comprising a lower bar and a pair of arms pivoted to the said depending arms, screw means for adjusting the friction of said arms about their pivots, and a plurality of flexible strips connecting said bars.

21. In a fender, the combination with a supporting frame, of a second frame pivoted thereto and comprising an upper bar and a pair of depending arms, each of said

- frames having a frictional surface which wedges against the frictional surface of the other to limit the rearward movement of the second frame, a third frame comprising a lower bar and a pair of arms pivoted to the said depending arms, screw means for adjusting the friction of said arms about their pivots, and a plurality of resilient strips connecting said bars.
- 10 22. In a fender, the combination with a supporting frame, of a second frame pivoted thereto and comprising an upper bar and a pair of depending arms, each of said

frames having a frictional surface which wedges against the frictional surface of the other to limit the rearward movement of the second frame, a third frame comprising a lower bar and a pair of arms pivoted to the said depending arms, screw means for adjusting the friction of said arms about their pivots, and a plurality of normally arcuate resilient strips connecting said bars.

In testimony whereof I hereunto affix my signature.

ARTHUR M. LEISSE.
